ATTORNEY

UNITED STATES PATENT OFFICE.

JOHN BRAUER, OF MENASHA, WISCONSIN.

SHIPPING-CASE-COVER FASTENER.

No. 884,890.

Specification of Letters Patent. Patented April 14, 1908.

Application filed November 25, 1907. Serial No. 403,614.

To all whom it may concern:

Be it known that I, JOHN BRAUER, a citizen of the United States, residing at Menasha, in the county of Winnebago, and 5 State of Wisconsin, have invented a new and useful Improvement in Shipping-Case-Cover Fasteners, of which the following is a specification.

My invention relates to a wire shipping case 10 cover fastener for use principally upon pails formed of staves and turned into a round form for packing cases, such as pails in which tobacco, candy, &c. are shipped from the wholesaler to the retailer, but is applicable 15 also to pails formed of fiber, veneer, metal, &c. or boxes made of various kinds of material and form, which may be used for similar shipping purposes, and the object of my invention is to provide a fastening device that 20 is easy to make, is of low cost and can be easily applied and one that can be applied in such a manner that it cannot be removed, the cover of the package removed and also some of the contents of the package and the cover 25 re-placed and also its fastening device, without said fastening device indicating by its mutilation, the probability of the contents of said package having been tampered with while in transit between the packer and shipper 30 and the consignee, so that if any loss takes place in transit, it will be apparent to the receiver and can be at once, and correctly located.

My invention is shown in the accompanying drawing, in which,

Figure 1 is an elevation in perspective of a pail having a cover, and a fastening device applied thereto. Fig. 2 is an elevation in perspective of a pail having a cover thereon, 40 and a fastening device of a modified construction applied thereto.

Similar numerals and letters indicate like parts in the several views.

1, indicates a pail; 2, its cover; 3, wire 45 hoops thereon, and 4, its bail secured with the usual staples 5.

6 and 6^a, indicate the wire fastening devices.

I will first describe the construction of the 50 device shown in Fig. 1. It consists of two pieces of wire, 7 and 8, of similar length, each end of each piece being inserted from the outside through a small bore 9, near the top of the pail, and a twist made in the wire or a 55 head and washer 10, provided upon the inside end of the wire so that it cannot be

pulled through said bore. The cover is broken through in the figures so as to show said washer upon the end of the wire. Each wire is then to be pulled up tightly against 60 said washer, twists or bends, and bent upward over the edge of the cover, the slack of the wires being then bent toward the center of the pail cover and the outer loops formed of the two wires 7 and 8 twisted around each 65 other, as shown at 11, until the several wires are drawn tightly over the cover for holding it in position. As the twisting of the wires requires a special tool for doing it, the wire cannot be untwisted, the cover removed and 70 the contents of the package abstracted and the cover replaced and the wire again twisted together, without the effects of such action being plainly shown by the kinks and mutilation of the wire. In order to make interference with the fastener more surely visible, 75 melted solder, 12, can be dropped upon the central eye of the twist, and a letter, or character, as X, impressed upon it and thereby providing a seal upon the fastener. 80

In the modification shown in Fig. 2, three separate wires, 13, 14 and 15, are shown, but more can be used if desired. The inner end of each piece is provided with a washer 10, upon its extremity, the same as the wires in 85 Fig. 1 for preventing the wires from being pulled through the bores 9. The outer end of each wire is bent upward and then toward the center of the cover, where they are all twisted together into a central twist 16, until 90 sufficiently tightened over the cover for holding it in position. Solder, 12, can be applied over the twist and a seal impressed upon it as in Fig. 1. The fasteners can be removed when required, by the use of the usual tinner's snips, or with a hammer and cold chisel. 95

Having described my invention, what I claim and desire to secure by Letters Patent, is,

1. A fastener for a pail or other shipping case cover, comprising a shipping case provided with a plurality of bores through the same near its upper end, a plurality of wires passing outward from the inner side of said bores, means for preventing the pulling 100 through said bores of the inner ends of said wires, said wires extending upward outside of the shipping case and over its cover to near its center, where all of the wires are twisted together until tightened sufficiently 105 for holding the cover in position thereon.
2. A fastener for a pail or other shipping

case cover, comprising a shipping case provided with a plurality of bores through the same near its upper end, a plurality of wires passing outward from the inner side of said bores, means for preventing the pulling through said bores of the inner ends of said wires, said wires extending upward outside of the shipping case and over its cover to near its center, where all of the wires are twisted together until tightened sufficiently for holding the cover in position thereon, and solder applied over the central portion of said twist.

3. A fastener for a pail or other shipping case cover, comprising a shipping case provided with a plurality of bores through the same near its upper end, a plurality of wires passing outward from the inner side of said bores, means for preventing the pulling through said bores of the inner ends of said wires, said wires extending upward outside of the shipping case and over its cover to near its center, where all of the wires are

twisted together until tightened sufficiently for holding the cover in position thereon, 25 solder applied over the central portion of said twist, and a seal impressed upon said solder consisting of a letter or a suitable character.

4. A fastener for a pail or other shipping case cover, comprising a shipping case provided with a plurality of bores through the same near its upper end, two wires each formed into a loop and each end of the wire of the loop passed through one of said bores, a suitable head formed on the end of each 35 wire inside of its bore for preventing said end from being pulled through said bore, the outer loops of said two wires being bent upward, over the edge of the cover and toward its central portion and twisted together until 40 sufficiently tightened for holding the cover in position upon the case.

JOHN BRAUER.
